PROCESS FOR PREPARING PYRROLIDINONES
AND PIPERIDINONES BY HYDROGENOLYSIS
Newman M. Bortnick, Oreland, and Marian F. Fegley,
Mont Clare, Pa., assignors to Rohm & Haas Company,
Philadelphia, Pa., a corporation of Delaware
No Drawing. Filed Oct. 13, 1959, Ser. No. 846,069
10 Claims. (Cl. 260—293.2)

This invention deals with a method for the preparation of specific pyrrolidinones and piperidinones.

The compounds that are prepared by the present invention may be represented by the formula

These compounds are produced by the hydrogenolysis of compounds having the formula

The symbol R represents a hydrogen atom, an alkyl group of one to eighteen carbon atoms, an aryl group of up to ten carbon atoms, an aralkyl group of up to eighteen carbon atoms, an alkarylalkyl group of up to thirty carbon atoms, an alkoxyalkyl group of three to twenty-four carbon atoms, a hydroxyalkyl group of two to twelve carbon atoms, and an alkylaminoalkyl group of three to eighteen carbon atoms provided that the amino group is a secondary or tertiary structure, that is non-primary. Alkyl, in the above definition, is to be construed to include cycloalkyl and alkylcycloalkyl within the range of carbon atoms previously set forth.

Typical R representations are methyl, ethyl, butyl, octyl, decyl, dodecyl, octadecyl, cyclopentyl, cyclohexyl, butylcyclohexyl, octylcyclohexyl, butylcyclohexyl, ethyl, phenyl, naphthyl, benzyl, phenylethyl, phenylbutyl, phenyldodecyl, methylphenyl, ethylphenyl, butylphenyl, octylphenyl, nonylphenyl, decylphenyl, hexadecyphenyl, octadecyphenyl, methylbenzyl, ethylbenzyl, butylbenzyl, octylbenzyl, dodecylbenzyl, butylphenylbutyl, octylphenylethyl, dioctylphenylethyl, dodecylphenyloctyl, methoxyethyl, methoxydodecyl, methoxyhexyl, methoxydecyl, methoxyoctadecyl, ethoxyethyl, ethoxybutyl, ethoxyoctyl, ethoxydodecyl, propoxyethyl, propoxybutyl, propoxyheptyl, propoxytetradecyl, butoxyethyl, butoxybutyl, butoxyoctyl, butoxydodecyl, butoxyoctadecyl, pentoxyethyl, pentoxybutyl, pentoxydecyl, hexoxyethyl, hexoxyhexyl, hexoxydodecyl, hexoxyoctadecyl, heptoxyethyl, heptoxyoctyl, octoxyethyl, octoxybutyl, octoxyoctyl, octoxydodecyl, nonoxypropyl, nonoxyheptyl, nonoxytridecyl, decoxyethyl, decoxyoctyl, undecoxybutyl, decoxypropyl, dodecoxydecyl, dodecoxydodecyl, tridecoxyethyl, tetradecoxypropyl, pentadecoxypentyl, hexadecoxypentyl, heptadecoxethyl, octadecoxethyl, octadecoxhexyl, hydroxyethyl, hydroxypropyl, hydroxybutyl, hydroxypentyl, hydroxyoctyl, hydroxydecyl, hydroxydodecyl, ethylaminoethyl, propylaminoethyl, butylamino-propyl, octylaminoethyl, hexylaminoethyl, heptylamino-pentyl, octylaminoethyl, nonylaminoethyl, ethylamino-nonyl, decylaminopropyl, propylaminododecyl, dodecylaminoethyl, dodecylaminopropyl, dodecylaminobutyl, decylaminohexyl, N-methyl-N-ethylaminoethyl, N-propyl-N-ethylaminoethyl, N-butyl-N-pentylaminoethyl, N-octyl-N-hexylaminobutyl, N-decyl-N-butylaminobutyl, N-N-dimethylaminoethyl, N,N-dipropylaminopropyl, N,N-

2

dicyclohexylaminobutyl, morpholinopropyl and pyrrolidinoethyl.

The symbol R¹ represents hydrocarbon groups of one to ten carbon atoms, preferably alkyl, arylalkyl, cycloalkyl, aryl, and alkaryl. R¹ may typically represent methyl, butyl, octyl, benzyl, phenylbutyl, cyclopentyl, cyclohexyl, phenyl, naphthyl, butyl phenyl groups, and the like.

The symbol R² stands for a hydroxyl group, an alkoxy group of one to four carbon atoms, such as methoxyl, ethoxyl, isopropoxyl, or butoxyl, or an alkylamino group in which the alkyl portion contains one to twelve carbon atoms, such as methyl, ethyl, hexyl, octyl, decyl, and dodecyl.

D is a divalent chain containing two to three carbon atoms. The carbon atoms in the D chain may have their remaining valences satisfied by hydrogen atoms, by alkyl groups whose total carbon atom content is no greater than 18, or by combinations of hydrogen atoms and alkyl groups. When D contains two carbon atoms, there are four valences to be satisfied by hydrogen atoms, alkyl groups, or combinations thereof. For instance, there may be four hydrogen atoms, four alkyl groups, three hydrogen atoms and one alkyl group, two hydrogen atoms and two alkyl groups, or one hydrogen atom and three alkyl groups. When D contains three carbon atoms, there are six valences to be satisfied by hydrogen atoms, alkyl groups, or combinations thereof and these valences may be satisfied in a way analogous to the manner described above when D contains two carbon atoms. It is also possible for the above-mentioned alkyl substituents to be joined together to form carbocyclic rings in conjunction with the D chain.

The alkyl substituents on the carbon atoms of the D chain may have any possible spatial configurations, such as normal, iso, tertiary, and the like. These alkyl substituents may also be straight chained or cyclic. Typical of the alkyl substituents that may be used to satisfy the remaining valences of the carbon atoms in the D chain include methyl, ethyl, propyl, butyl, cyclopentyl, hexyl, cyclohexyl, octyl, decyl, dodecyl, tridecyl, tetradecyl, and octadecyl groups.

Illustrative of the compounds that may be employed as reactants in the present invention include

- 45 1,4,5-trimethyl-5-hydroxy-2-pyrrolidinone,
- 1,3,5-trimethyl-3-(2,2-dimethylpropyl)-5-methoxy-2-pyrrolidinone,
- 1,3-dimethyl-3,5-dihexyl-5-methyl-amino-2-pyrrolidinone,
- 7a-hydroxy-1-methyl-3,3-pentamethylene-2,3,3a,4,5,6,7,7a-octahydroindol-2-one,
- 1-ethyl-3,3,5-trimethyl-5-(2-ethylhexoxy)-2-pyrrolidinone,
- 1-ethyl-3-methyl-3,5-dipropyl-5-hydroxy-2-pyrrolidinone,
- 3-butoxy-2-ethyl-3,7a-dimethyl-1,3,3a,4,5,6,7,7a-octahydroisoindol-1-one,
- 1-(2-phenylethyl)-3,3,5-trimethyl-5-hydroxy-2-pyrrolidinone,
- 1-(2-dimethylaminoethyl)-3,3,5-trimethyl-5-(2-dimethylaminoethylamino)-2-pyrrolidinone,
- 1-(2-methylaminopropyl)-3,3,5-trimethyl-5-hydroxy-2-pyrrolidinone,
- 3,3,5-trimethyl-5-hydroxy-2-pyrrolidinone,
- 3,5-dimethyl-3-neopentyl-5-hydroxy-2-pyrrolidinone,
- 1-(2-methyl-2-propylaminopropyl)-3,5-dihexyl-3-methyl-5-methoxy-2-pyrrolidinone,
- 7a-methoxy-1-(3-dimethylaminopropyl)-3,3-pentamethylene-2,3,3a,4,5,6,7,7a-octahydroindol-2-one,
- 1-(4-diethylaminophenyl)-3,3,5-trimethyl-5-hydroxy-2-pyrrolidinone,
- 3,5-dihexyl-3-methyl-5-methoxy-2-pyrrolidinone,
- 1-(4-dimethylaminophenyl)-3,3,5-trimethyl-5-hydroxy-2-pyrrolidinone,

1-benzyl-3,3,5-trimethyl-5-hydroxy-2-pyrrolidinone,

 1-phenyl-3,5,5-trimethyl-6-hydroxy-2-piperidinone,
 1-butyl-3,5-dibutyl-6-methyl-6-methoxy-2-piperidinone,
 and 1-benzyl-3,6-dibutyl-5-methyl-6-hydroxy-2-piperidinone.

The present invention involves the hydrogenolysis of specific pyrrolidinones and piperidinones. This method is carried out in the presence of a catalyst. Suitable as catalysts are Raney nickel, Raney cobalt, cobalt with ammonia, nickel with ammonia, cobalt-copper, nickel-cobalt, palladium, platinum, rubidium, ruthenium, and the like. The catalyst may be employed in any convenient particle size. Generally, the smaller particle sizes produce the higher yields. If desired, the catalyst may be deposited on a carrier material in order to extend and activate it. Suitable for use as a carrier are activated alumina, activated clays, silica gel, charcoal, asbestos, pumice, and the like. Room temperatures and somewhat above, such as 30° C. and above, may be employed when a noble metal is used as the catalyst. When the other materials are employed as catalysts, temperatures in the range of about 75° to 250° C. are employed with about 100° to 200° C. preferred. An inert, volatile, organic solvent may be desirable, such as hydrocarbons, alcohols, ethers, and the like. The lower alkanols, such as methanol or ethanol, are particularly suited for this use. When the noble metals are used as catalysts, a small amount of an activating acid, such as acetic or hydrochloric may be employed.

When a noble metal is employed as the catalyst, pressures in the range of atmospheric to 10 atmospheres may be employed. When the other listed substances are used as catalysts, pressures in the range of 10 to 1000 atmospheres or more are used. A preferred way of consummating the instant reaction is to introduce the pyrrolidinone or piperidinone reactant along with a catalyst of the type described heretofore into a pressure retention reaction vessel and add hydrogen until a certain desired pressure is reached. The reaction vessel or at least the reaction ingredients may be preferably agitated such as by stirring or rotating until a precalculated drop in pressure is observed. This significant drop in pressure indicates that an equivalent amount of hydrogen has reacted. This precalculated pressure drop indicating that an equivalent amount of hydrogen has reacted is readily calculable by known methods. Therefore, an indication of reaction completion may be readily calculated and observed. The actual time for total reaction will, of course, vary depending, more or less, upon reaction conditions and the individual reactants employed.

The piperidinone and pyrrolidinone reactants employed in the present process may be obtained by cyclization of γ - and δ -oxonitriles. It is possible to start with γ - and δ -oxonitriles and, by cyclization and hydration employing aqueous amines, obtain the corresponding 5-hydroxy-2-pyrrolidinone and 6-hydroxy-2-piperidinone reactants. The corresponding 5-alkoxyl and 6-alkoxyl reactants may be derived from their hydroxy counterparts by reaction with an alkanol in the presence of alkali and the 5-amino and 6-amino reactants may be obtained from their hydroxyl counterparts by heating with an amine. Hydrogenolysis of any of these leads to the corresponding 2-pyrrolidinones and 2-piperidinones as described heretofore. Thus, it is possible to go from the γ -oxonitriles and δ -oxonitriles to the 2-pyrrolidinones and 2-piperidinones in a rather continuous way without the necessity of separating or purifying the 5-hydroxy-2-pyrrolidinones or 6-hydroxy-2-piperidinones. It is, of course, generally desirable, from the viewpoint of yields, to employ as reactants the specific pyrrolidinones and piperidinones discussed heretofore. The products obtained have known utilities.

At the conclusion of the reaction, the product is obtained by filtering off the catalyst and stripping off the

solvent. If desired, the products may be purified by distillation or recrystallization from hydrocarbons, ethers, or the like.

The method of this invention may be more fully understood from the following examples which are offered by way of illustration and not by way of limitation. Parts by weight are used throughout.

Example 1

A mixture of 3,3,5-trimethyl-5-hydroxy-2-pyrrolidinone (71.5 parts), methanol (35 parts), and Raney nickel (3.5 parts) is pressurized with hydrogen at 1200 p.s.i.g and 170° to 186° C. for two hours. The reaction mixture is filtered to remove the catalyst and then stripped to remove methanol. The crude product (62 parts) has a melting point of 82° to 89° C. Recrystallization from chloroform gives the purified product having a melting point of 92° to 93° C. and a nitrogen content of 10.98% (theoretical for $C_7H_{13}NO$ —11.01%).

In a similar way, are prepared 1-benzyl-3,3,5-trimethyl-2-pyrrolidinone from 1-benzyl-5-hydroxy-3,3,5-trimethyl-2-pyrrolidinone, 1-(2-phenylethyl)-3,3,6-trimethyl-2-piperidinone from 1-(2-phenylethyl)-6-hydroxy-3,3,6-trimethyl-2-piperidinone and 1-(2-hydroxypropyl)-5,5-dimethyl-2-piperidinone from 1-(2-hydroxypropyl)-5,5-dimethyl-6-hydroxy-2-piperidinone.

Example 2

3,5-dimethyl-3-neopentyl-5-hydroxy-2-pyrrolidinone (100 parts), ethanol (60 parts), and Raney nickel (3.5 parts) absorb hydrogen at 140° C. and 1500 p.s.i.g. to give on filtration and evaporation of solvent 3,5-dimethyl-3-neopentyl-2-pyrrolidinone (93 parts) having a melting point of 80° to 99.5° C. and a nitrogen content of 7.53% (theoretical for $C_{11}H_{21}NO$ —7.65%). The yield is quantitative. Since the methyl groups in this compound can be either cis or trans to one another, the wide melting point range indicates that a mixture of the two possible racemates is obtained.

In like manner, are prepared 1-(2-methylaminoethyl)-3,5-dimethyl-3-hexyl-2-pyrrolidinone from 1-(2-methylaminoethyl)-3,5-dimethyl-3-hexyl-5-hydroxy-2-pyrrolidinone and spiro{3,3-dimethylbicyclo(2.2.1)heptane-2,3'-(5'-methyl-2'-pyrrolidinone)} from spiro{3,3-dimethylbicyclo(2.2.1)heptane-2,3', [5-methyl-5'-hydroxy-2'-pyrrolidinone]}.

Example 3

6-hydroxy-5,5-dimethyl-2-piperidinone (20 parts) and water (50 parts) and Raney nickel (1 part) are charged to the hydrogenation reactor and heated at 140° to 148° C. under hydrogen at 2000 p.s.i.g. for two hours. The filtered reaction is distilled to give a product which boils in the range of 103° to 180° C. (0.4 mm. absolute pressure). Recrystallization from a mixture of heptane and ethanol gives the pure product, having a melting point of 120° to 124° C. and a nitrogen content of 10.85% (theoretical for $C_7H_{13}NO$ —11.01%). The product has the structure 5,5-dimethyl-2-piperidinone.

Analogously, 1-p-tolyl-3,3,5-trimethyl-5-hydroxy-2-pyrrolidinone gives 1-p-tolyl-3,3,5-trimethyl-2-pyrrolidinone, 1-(2-hydroxyethyl)-3,5-bis(2-methylpropyl)-3-methyl-5-hydroxy-2-pyrrolidinone gives 1-(2-hydroxyethyl)-3,5-bis(2-methylpropyl)-3-methyl-2-pyrrolidinone and 1-(3-dimethylaminopropyl)-4,6-dimethyl-4-neopentyl-6-methoxy-2-piperidinone gives 1-(3-dimethylaminopropyl)-4,6-dimethyl-4-neopentyl-2-piperidinone.

Example 4

2,2-dimethyl-4-oxopentanone (71 parts) is added to 0.2 N sodium hydroxide solution (60 parts by volume). The mixture is stirred at 25° to 45° C. for 16 hours. The mixture is transferred to a hydrogenation reaction vessel and Raney nickel (7.5 parts) is added. The mixture is pressurized with hydrogen at 2000 p.s.i.g. during three hours at 100° to 140° C. The reactor is vented, the re-

action mixture is filtered and the low boiling materials are removed by stripping under reduced pressure. The residue is dissolved in benzene and filtered to remove inorganic salts. The combined first crop (54 parts), melting point 89° to 91° C., and second crop (7.5 parts) represent a yield of 86% of the product, 3,3,5-trimethyl-2-pyrrolidinone.

Example 5

To 0.6 N sodium hydroxide (41 parts) is added 3-methyl-4-oxopentanone (56 parts) over a period of 70 minutes. A 17° C. rise in temperature is observed. Sodium hydroxide (1 part) is added after the exothermic reaction has subsided and the reaction mixture is stirred overnight at room temperature. The entire reaction mixture, methanol (10 parts by volume) and Raney nickel (8 parts), is charged to a hydrogenation reactor and hydrogenated at 2000 p.s.i.g. of hydrogen and 140° C. The theoretical amount of hydrogen is absorbed. The reactor is vented, catalyst is removed by filtration and the filtrate is distilled. The product has a boiling point of 88° to 92° C. (0.05 mm. absolute pressure), and n_{D}^{25} value of 1.4701, and is obtained in 63% yield. The product contains 12.10% nitrogen (theoretical for $C_6H_{11}NO$ —12.37%).

The procedures of Examples 4 and 5 are very useful methods applicable to a wide variety of hydroxylactams and their parent γ - and δ -ketonitriles. Thus, following the procedure of Example 4, 1-(2-oxocyclohexyl)-cyclohexanecarbonitrile gives 3,3-pentamethylene-2,3,3a,4,5,6,7,7a-octahydroindol-2-one, 2-acetylcylohexanecarbonitrile gives 3-methyl-1,3,3a,4,5,6,7,7a-octahydro-1-isoindolone, 4-methyl-5-oxohexanone gives 5,6-dimethyl-2-piperidinone, 4-oxopentanone gives 5-methyl-2-pyrrolidinone, 2-oxo- α , α -4-trimethylcyclohexaneacetonitrile gives 3,3,6-trimethyl-2,3,3a,4,5,6,7,7a-octahydro-2-indolone, and 1,3,3-trimethyl-5-oxycyclohexanecarbonitrile gives 6-aza-7-oxo-1,3,3-trimethylbicyclo(3.2.1)octane.

Example 6

5-methoxy-3,3,5-trimethyl-2-pyrrolidinone (50 parts), methanol (50 parts by volume), and Raney nickel (2 parts) are charged to a hydrogenation autoclave and pressurized at 1500 p.s.i.g. The temperature is held at 120° to 150° C. during the two hours which are required for hydrogenation to proceed to completion as judged by cessation of the fall of pressure. The mixture is cooled, vented, and filtered. The filtrate is stripped of methanol and the residue (which crystallizes on cooling) is recrystallized from heptane to give the product, 3,3,5-trimethyl-2-pyrrolidinone in 92% yield.

In a similar manner, 4,5-dimethyl-2-pyrrolidinone is made from 5-butoxy-4,5-dimethyl-2-pyrrolidinone; 5,5-dimethyl-2-piperidinone is made from 6-ethoxy-5,5-dimethyl-2-piperidinone; 5-ethyl-5-butyl-2-piperidinone is made from 6-methoxy-5-ethyl-5-butyl-2-piperidinone; and 3,5-dihexyl-3-methyl-2-pyrrolidinone is prepared from 5-propoxy-3,5-dihexyl-2-methyl-2-pyrrolidinone.

Example 7

1-benzyl-5-benzylamino-3,3,5-trimethyl-2-pyrrolidinone (75 parts), methanol (100 parts), and Raney cobalt (10 parts) are shaken in a rocking autoclave under a hydrogen pressure of 1500 p.s.i.g. at 150° C. until no further pressure drop is observed. The mixture is cooled, vented and filtered. The solvent and benzylamine which is formed in the process are removed under reduced pressure. The product, 1-benzyl-3,3,5-trimethyl-2-pyrrolidinone, has a boiling point of 130° to 140° C. (3 mm. absolute pressure). The same product is formed when 5-hydroxy-3,3,5-trimethyl-1-benzyl-2-pyrrolidinone is hydrogenated in aqueous medium in the presence of Raney nickel. In a similar fashion, 5-methylamino-1,3,3,5-tetramethyl-2-pyrrolidinone gives 1,3,3,5-tetramethyl-2-pyrrolidinone.

Similarly, 1,3-dimethyl-3,5-dihexyl-5-methyl-

amino-2-pyrrolidinone gives 1,3-dimethyl-3,5-dihexyl-2-pyrrolidinone, 1 - ethyl - 3,3,6 - trimethyl - 6 - ethylamino - 2 - piperidinone gives 1 - ethyl - 3,3,6 - trimethyl - 2 - piperidinone, and 1 - dodecyl - 3,5,5 - trimethyl - 6 - butylamino - 2 - piperidinone gives 1 - dodecyl - 3,5,5-trimethyl-2-piperidinone.

We claim:

1. A method for the preparation of a compound having the formula

which comprises hydrogenolysis of a compound having the formula

in which R is a member of the group consisting of hydrogen, alkyl of one to eighteen carbon atoms, aryl of up to ten carbon atoms, aralkyl of up to eighteen carbon atoms, alkarylalkyl of up to thirty carbon atoms, alkoxy-alkyl of three to twenty-four carbon atoms, hydroxy-alkyl of two to twelve carbon atoms, and alkylamino-alkyl of three to eighteen carbon atoms in which the amino group is non-primary in structure, R¹ is a member from the group consisting of alkyl, arylalkyl, cycloalkyl, aryl, and alkaryl of up to ten carbon atoms, R² is a member of the group consisting of hydroxyl, alkoxy of one to four carbon atoms, and alkylamino in which the alkyl portion contains one to twelve carbon atoms, and D is an alkylene chain containing two to three carbon atoms between the carbon atoms to which said D is attached, the remaining valences of said two to three carbon atoms of said D are satisfied by members of the group consisting of hydrogen atoms, alkyl groups having a total carbon atom content of up to eighteen

and combinations of said hydrogen atoms and said alkyl groups, by reaction with substantially one equivalent of hydrogen at a temperature of at least about 30° C. in the presence of a hydrogenolysis catalyst which is a member from the class consisting of Raney nickel, Raney cobalt, cobalt with ammonia, nickel with ammonia, cobalt-copper, nickel-cobalt, palladium, platinum, rubidium, and ruthenium.

2. A method according to claim 1 in which D is a divalent chain containing two carbon atoms.

3. A method according to claim 1 in which D is a divalent chain containing three carbon atoms.

4. A method according to claim 1 in which the hydrogenolysis agent is a noble metal and the reaction is conducted at a pressure of from atmospheric to ten atmospheres.

5. A method according to claim 1 in which the reaction is conducted at a temperature of 75° to 250° C. and at a pressure of at least 10 atmospheres.

20 6. A method according to claim 1 in which the reaction is conducted in the range of 100° to 200° C. and at 10 to 1000 atmospheres of pressure.

7. A method according to claim 4 in which the reaction is conducted in the presence of an activating acid 25 for a noble metal hydrogenolysis agent which is a member from the class consisting of acetic acid and hydrochloric acid.

8. A method according to claim 1 in which the reaction is conducted in the presence of an inert volatile 30 organic solvent.

9. A method according to claim 1 in which the hydrogenolysis agent is Raney nickel.

10. A method according to claim 1 in which the hydrogenolysis agent is Raney cobalt.
